UNITED STATES PATENT OFFICE

GEORGE SAMUEL HOLLY, OF ST. CHARLES, ILLINOIS, ASSIGNOR TO UNITED REPRODUCERS CORPORATION, OF ROCHESTER, NEW YORK, A CORPORATION OF NEW JERSEY

PHONOGRAPH

Application filed April 10, 1929. Serial No. 354,114.

The present invention relates to phonographs, talking machines and the like, and has reference more particularly to the portable type thereof.

5 Among the objects of the invention is to provide a novel device having relatively movable sections which in one relation will be the closed condition of the device, and in another relation will be the open and playing condition of the device, each section carrying a sound amplifying device segment, such as a horn, an air column sound amplifier or the like with or without, but preferably with exponential characteristics, 10 such that when the apparatus is open and in playing position, condition or relation, the segments will join and form a continuous acoustic amplifier. One of the sections may carry means for reproducing sound from a record, and means for operating the record for sound reproduction, and another section 15 may have a compartment for the storing of a number of records.

Another object is to provide novel means 20 for flexibly connecting the sections whereby one may be easily and properly moved relative to the other to and from closed or superimposed position, and open or upright position so as to abut the other section. Both 25 sections preferably have openings which will register when they are in abutting relation and the outlet of one segment being in one of said openings and the inlet of the other segment being in the other of said openings 30 so that when the openings register, said inlet and outlet will join and the segments thus 35 form a single continuous amplifier.

Other objects, capabilities, advantages and 40 features are comprehended by the invention as will later appear and as are inherently possessed thereby.

Referring to the drawing:

Fig. 1 is a side view of the device in closed 45 position.

Fig. 2 is a similar view of the device in open position, with a part broken away.

Fig. 3 is a rear view in elevation of the 50 device in closed position.

Fig. 4 is a transverse sectional view taken

in a plane represented by line 4—4 in Fig. 3 of the drawing; and

Fig. 5 is a similar view of the device when 55 in open position and showing the joining of the segments of the amplifier and the abutting relation of one section with the end of the other section.

Referring now more in detail to the drawing, the embodiment selected to illustrate 60 the invention is shown as comprising a lower section 1 and an upper section 2 connected together flexibly by links 3 and 4 having pivot connections 5, 6, 7 and 8.

The lower section has a partition 9 suitably supported by elements 10 and 11 secured 65 to the side walls of the section. Below this partition may be suitably located an operating mechanism 12 which may be in the form of a spring motor or any other suitable operating device as desired. The operating device 12 operates through a turn-table shaft 13 extending above the partition 9 and carrying a turn-table 14 upon which may be placed a record when the device is used for playing. 70

Supported upon the partition 9 is a goose 75 neck 15 having a tone arm 16 leading to a sound box or reproducing device 17 which may have a stylus 18 adapted to cooperate with the groove of a record when playing the device. The larger end of the goose neck 80 15, besides being secured to the partition 9, communicates through an opening in the partition with an inlet part 19 of an amplifying device. The part 19 flares or expands 85 into amplifier part 20 extending through the space in the section 1 toward the front portion thereof, and continuing through part 21, which in turn continues through part 22. The outlet 23 of part 22 extends to an opening 24 in the rear wall 25 of the lower section 90 1, as clearly shown in the drawing. The parts 19, 20, 21 and 22 constitute one of the segments of the sound amplifier, and are wholly housed within the section 1 and carried thereby. If desired, any suitable filling 95 material may be placed in the chamber of the section 1 and around the parts when it is desired to decrease the dissipation of sound vibrations or to prevent resonance. Such filling material might be of the type, which when 100

heated, will be liquid or plastic, and upon cooling will solidify about the amplifier parts. In section 2 is located an amplifier segment 26 having its inlet 26^a registering with an opening provided in wall 27 of this section and registering with the opening 24 of section 1, when section 2 is in upright position, as shown in Fig. 5. The amplifier segment 25 has a bell 28 having its discharge opening 29 in the wall 27 as shown.

In the space above the bell 28 is provided a suitable partition 30 extending from the front wall of the section 2 and over a part of the amplifier segment 25 and to the top wall of section 2. This is clearly shown in Figs. 4 and 5. This partition defines a compartment 31 in which may be placed a number of records 32. At the front of the section may be provided a door 33 suitably connected by way of a hinge 34, to the remainder of the front wall of the section. This hinge may be of the spring type which normally maintains the door closed, but will yield upon pressure of the hand to give access to the compartment 31 for taking or storing records therein.

Suitable handles and knobs may be used as desired on the device, it being considered unnecessary to show them here.

The device is of the portable type and of sufficiently small dimensions so that it may be carried readily from place to place without inconvenience, yet is such that all the advantages in phonograph playing with the present day tone renditions of a large phonograph is possessed by this device. In the closed condition, section 2 superimposes section 1, and acts as a cover or closure for section 1 whereby all of the parts are enclosed. Only the opening 24 is exposed to the exterior. When it is desired to play a record, section 2 is lifted and by reason of the links 3 and 4, section 2 will first be lifted from section 1 and swung to the rear into upright position, and as it swings downwardly, will be brought into proper abutting relation with the rear wall of section 1, that is to say, wall 27 of section 2 will abut the rear wall of section 1 and bring the openings in these two walls in exact registry. Inasmuch as the outlet of the amplifier segment in section 1 and the inlet of the amplifier segment in section 2 are disposed in these openings, the inlet and outlet mentioned will join together so that the segments of the amplifier will form a single continuous amplifier.

When section 2 is to be moved into closed condition, the links 3 and 4 will so operate as to first move the lower end of section 2 away from the rear wall of section 1 and then the section will rise into a position above section 1 and then move downwardly into proper position as shown in Fig. 1. At the parting between and at the front of sections 1 and 2, suitable latching or locking means may be

provided as desired, as also a handle whereby the device may be carried from place to place.

While I have herein disclosed and upon the drawing shown an illustrative embodiment of the invention, it is to be understood that the invention is not limited thereto but may comprehend other constructions, details, arrangements of parts and features without departing from the spirit thereof.

Having thus disclosed the invention, I claim:

1. A phonograph comprising a body, a cover, means carried by the body for operating a record, a sound amplifier comprising a segment carried by the body and a segment carried by the cover, said segments joining when the cover is open to form a continuous amplifier, and links connected to said body and said cover for flexibly connecting the same. 85

2. A phonograph comprising a body, a cover, links pivotally connected to said body and cover, means carried by the body for operating a record, a sound amplifier comprising a segment carried by the body and a segment carried by the cover, said segments joining when the cover is open to form a continuous amplifier, said segment in said cover having a sound discharge opening in said cover for delivering the sound to the atmosphere when the cover is in open position. 90

3. A phonograph comprising flexibly connected sections, links for flexibly connecting said sections, means in one of said sections for operating a record and reproducing sound therefrom, a segmental sound amplifier having a segment in each of said sections, said segments being joined to form a continuous amplifier when said sections are extended. 100

4. A phonograph comprising flexibly connected sections, links for flexibly connecting said sections, means in one of said sections for operating a record and reproducing sound therefrom, a segmental sound amplifier having a segment in each of said sections, said segments being joined to form a continuous amplifier when said sections are extended, the segment having the sound discharge opening being in an extended section. 110

5. A phonograph comprising flexibly connected sections, links for flexibly connecting said sections, means in one of said sections for operating a record and reproducing sound therefrom, a segmental sound amplifier having a segment in each of said sections, said segments being joined to form a continuous amplifier when said sections are extended, the segment having the sound discharge opening being in another section from the section having the record operating and reproducing means. 120

6. A phonograph comprising a lower section having an opening in a wall thereof, 130

means for operating a record and for reproducing sound therefrom, an amplifier segment in said section and ending at said opening, an upper section adapted in one position to cover the lower section and in another position to be adjacent said wall, links pivotally connected to said sections for flexibly connecting said sections, an amplifier segment in said upper section and having an end thereof registering with the end of the amplifier of said lower section at said opening when said upper section is in said another position.

7. A phonograph comprising relatively movable sections, links connecting said sections for the moving of one of said sections from a superimposed position with the other section, to an upright position and abutting relation with a side wall of said other section, means for reproducing sound from a record, and amplifier segments in said sections and having joining ends in openings provided in the abutting parts of said sections when said sections are in said abutting relation.

25 In witness whereof, I hereunto subscribe my name to this specification.

GEORGE SAMUEL HOLLY.
